UNITED STATES PATENT OFFICE.

J. S. BROWN, OF WASHINGTON, DISTRICT OF COLUMBIA, ASSIGNOR TO
HIMSELF AND C. P. STIMETS, OF NEW YORK, N. Y.

TOY AUTOMATON.

Specification forming part of Letters Patent No. 40,891, dated December 8, 1863.

To all whom it may concern:

Be it known that I, J. S. BROWN, of Washington, in the county of Washington and District of Columbia, have invented a new and Improved Toy Automaton or Doll Androïdes; and I do hereby declare that the following is a full and exact description thereof, reference being had to the accompanying drawings, making part of this specification—

Figure 1 being a central vertical section of the automaton in a plane from front to back; Fig. 2, a front elevation of the mechanical part or "movement" separate, the feet or "boots" being in section; Fig. 3, a side elevation of one of the feet or boots; Fig. 4, a modification of a portion of the working parts.

Like letters designate corresponding parts in all of the figures.

The principle on which my invention is produced consists in employing the supporting-foot as a stationary center, around which the raised foot turns in moving forward, the two feet acting alternately in the performance of these successive functions. For the purpose of raising and moving forward the feet, I make use of the rolling action of small wheels or disks L L, pivoted in the feet M M, turning forward with equal speed, and opposite portions of the two being alternately outside or below the lower plane of the feet and within or above the same. The effect is, as the projected portion of each wheel comes round alternately, to lift the foot in which it turns from the walking-surface or floor and roll it forward till raised within the supporting plane of the foot, at which moment the foot is brought again down to the floor, and the other foot is raised then and moved forward in the same way. There are various ways of constructing and arranging these wheels so as to be thus alternately exposed beyond and drawn within the supporting plane of the feet. The simplest and most effectual method is to give the wheels substantially the form shown in the drawings. About one half of the circumference is reduced in radius, so as not to reach below the foot, and the other half or portion of the circumference is of such radius as to project beyond the foot sufficiently to raise the foot as high as desired, which need be only a little distance. The rear extremity of

this enlarged part of the wheel should quite gradually approach the small portion of the same, so as to let the foot down slowly and gently; but the forward extremity may be more abrupt, as represented. The corresponding portions of the two wheels should be exactly opposite in position, so as to make the feet act alternately, and they should be so arranged that nearly at the moment one touches the floor the other should leave it, in order to produce the most perfect action. Another method of construction would be to have the wheels simply eccentric, acting alternately. Another equivalent means would be to have the wheels of an exactly circular form, but simply exposed alternately either by moving them up and down in the feet or by raising and lowering alternately the soles or heels of the two feet. This is a mere possible way, but neither so simple nor so practicable as that represented.

In order to adjust the relative space which each foot should move forward accurately, and to enable the automaton to move either straight forward or in a curve, as desired, I provide for adjusting the feet or boots M M up or down on the legs of the frame A A of the movement. This is done in the simplest manner by simply making a slot, t, Fig. 3, therein, through which a screw, m, is inserted and turned into a screw-hole in the frame till the foot is clamped firmly and immovably thereto. This adjustment exposes more or less rolling circumference of the wheels L L, and consequently increases or diminishes the space over which they move the feet. The driving power may be the ordinary coiled spring, B, on a winding-shaft, b, with a driving-wheel, C, and ratchet-wheel e thereon, the wheel C gearing into a pinion, f, on another shaft, d, below. There may be several means of communicating uniform and equal motion from this shaft d to the respective stepping-wheels L L in the feet. The method shown in Figs. 1 and 2 is preferred, as being the simplest, perhaps the cheapest, and certainly the surest in its action and least liable to become disarranged or broken. It consists, simply, in a set of cog-gearing, D G H I, running down each leg, the last cog, I, being secured fast to the wheel L. These communicating wheels, except the two drivers D D, may turn on mere station-

ary pivots, *g h i*, riveted to the side parts or legs of the frame *A*.

Another method of communication is indicated in Fig. 4. It consists in the employment of chains *E E* or perforated bands, or their equivalents, passing around spur-wheels *D I*, respectively, on the driving-shaft *d* and stepping-wheels *L L*. The alternate links of the chain or perforations in the band fit over spurs or projections *e e* on the wheels.

Another method of gearing would be the use of vertical connecting shafts with pinions thereon matching into crown-wheels or bevel-wheels, respectively, on the shaft *d* and wheels *L L*; or connecting-rods and cranks or eccentrics might be used, though defective in action.

The movement requires a regulator, any suitable kind of which may be employed. That shown in the drawings consists of the ordinary fly, *p*, on the shaft *P*, provided with a short-screw-thread, *n*, into which a spur-wheel, *N*, Fig. 2, (not shown in Fig. 1, but its relation to the screw being indicated by the wheel *D* of the same size, and on the same shaft gears,) The wheel *N* is in a plane passing through the axis of the fly-shaft *P*. One end of the fly-shaft *P* turns in a bearing on a cross bar, *s*, which also stays the lower part of the frame-strip *A*. This and a brace-bar, *a*, above, to which the driving-spring *B* is attached, constitute all that is required to secure the frame-piece *A*, which may be made in a single piece, as shown. The motion of one foot swinging around the other or the heel thereof as a center, if a similar motion should be given to the bust or upper and outer part of the doll, would be awkward and unnatural in appearance; but advantage is taken of this to produce even a more natural and life-like action of the doll. This is accomplished thus: A simple pivot-pin, *Q*, projects vertically upward from the center and upper end of the frame-piece *A*, and is pointed at the upper extremity, as shown in Fig. 1. A block, *T*, or its equivalent, to which the bust *S* of the doll is secured, is provided with a hole, *R*, of a taper or equivalent form, to allow not only the bust to turn freely around the pivot *Q*, but to allow it to

swing a little laterally in all directions. The bust has a metallic or other hard step, *r*, countersunk at the center, as shown, situated in the upper end of the hole *R*, to rest upon the point of the pivot *Q*. The bust is thus suspended thereon, the center of gravity being below the point of suspension; but it is prevented from turning too much upon the pivot by a cord, *o*, or its equivalent, secured to the lower end of the block *T* and to the frame-piece *A*, as shown in Fig. 2, so as to permit the bust to turn, and only about as much of a circle as the legs below turn in the act of walking. The motion of walking thus only communicates enough motion to the bust above to give a life-like appearance to the automaton. The dress *w* is suspended from the bust, around and away from the movement. This is also surrounded by an "under-garment," *v*, drawn up around it, and kept out away from the working parts by wire "hoops" or rings *u u*, soldered at intervals to the frame *A*, as indicated in Fig. 1.

What I claim as my invention, and desire to secure by Letters Patent, is—

1. Producing the walking motion by propelling each foot forward alternately in the arc of a circle around the other foot as a stationary center or pivot.
2. The alternately-acting wheels *L L*, for propelling the feet forward, having an intermittent moving action, so as to make the feet progress in succession, substantially as herein set forth.
3. Adjusting the feet up and down on the legs or frame, so as to vary or adjust the steps as desired, substantially as herein specified.
4. Suspending and pivoting the bust of the automaton upon the movement thereof, substantially as and for the purposes herein described.
5. The wire hoops or rings *u u*, for securing a covering around without interfering with the movement, as specified.

J. S. BROWN.
